VEHICLE CONTROL MECHANISM

John Good, Garden City, N. Y., assignor to Good Inventions Co., Garden City, N. Y., a corporation of New York

Application August 11, 1930, Serial No. 474,538

11 Claims. (Cl. 123—179)

The invention relates to the control of automotive vehicles, the object being to facilitate the driving thereof and consists of means operating without special attention on the part of the driver 5 to increase the engine fuel supply above the normal idling rate on occasions when the engine is otherwise likely to stall from insufficient fuel supply, as, for example, when shifting gears, or immediately after cranking the engine before it is 10 warmed up, a further object being to cause the increased fuel delivery, however effected, to persist for a period and terminate automatically that is, without conscious attention by the driver, when the conditions most favorable to engine stall have 15 been passed.

The drawing herewith is to be taken merely as exemplification of the principle of the invention and not as limitation. Fig. 1 represents a conventional automobile engine, with one form of the 20 invention applied to it;

Fig. 2 is a larger scale detail of the interrelated means for increasing the engine speed;

Fig. 3, the same in the accelerated condition;

Fig. 4 represents a developed form of the 25 same type of apparatus as applied to the button which controls the electric cranking of the engine; and

Figs. 5 and 6 are respectively different positions of that mechanism.

30 In Fig. 1, the propelling engine of the vehicle has a fuel supply system represented by the usual carburetor 1, with a throttle 2 connected by a link 3, bell crank 4 and push rod 5 with the accelerator pedal 6 herein referred to as the operator's normal engine control element, and which may be either hand or foot-operated, or both. The throttle is urged to its closed position by the usual 35 throttle spring, such as 7, and has an adjustable idling screw 8 preventing its complete closure. This screw, it will be understood, is intended to be set so as to establish a minimum opening of the throttle, when the operator's control has been removed, sufficient to keep the engine turning over when free of load. Whenever the 40 operator removes his foot from the control element 6, the throttle automatically returns, under the influence of the spring, to the idling position as determined by the set screw 8. The foregoing arrangement of fuel supply system will be 45 recognized as conventional and will be taken to exemplify any type of fuel system, suction-operated or otherwise, for the propelling engine of a self-impelled vehicle.

With the system described, or its equivalent, 50 the present invention combines a device to in-

crease the rate of fuel delivery to the engine above that determined by its idling means whatever the nature of that means, and to maintain such increased delivery and increased engine speed for a period of time following the act which 5 brought it about, which period is terminated as an incident to the operation or use of one of the existing control elements of the vehicle, being thus automatic in the sense that it is without conscious attention on the part of the driver. 10

The speed increasing means may take various forms as will presently be apparent since any device or arrangement which delivers, or causes to be delivered, to the engine a portion of fuel in excess of, or in addition to, that received by it 15 for its normal idling operation, will suffice for the purpose. The form shown in Figs. 1-3 consists of a cam or bevelled bolt guided in a suitable support marked 9 and suitable connections presently referred to. The bevelled end of the bolt is marked 10 and its straight side 11. It is so arranged as to be adapted to be moved or pushed under or over one of the joint-pins or the hub-joint 12 or any other part of the throttle-linkage system, so that by its wedging action it will 20 move the joint or part in the appropriate direction (downward) and to a sufficient extent to open the throttle slightly wider than its normal idling position, or prevent its closing completely 25 to the idling position, if already opened, thus increasing the fuel delivery and the engine speed somewhat above the normal idling rate, or preventing the delivery from being reduced to that rate. Fig. 3 shows the cam or bolt advanced into this accelerated setting with the linkage hub 30 now resting on its straight side 11. The bolt is under the pressure of a spring 13, tending to withdraw it from engagement with the linkage system, but not strong enough to move it against the side pressure and friction produced by the pressure of the hub 12 thereon, under the influence of the throttle spring, and the bolt is therefore retained or locked in its advanced setting until such throttle-spring pressure is removed. The speeded-up condition of the engine continues 35 until the throttle is opened still wider thus restoring or unsetting the bolt by allowing the spring 13 to act to withdraw it. It may be observed that there are two speed increasing means, one being the normal throttle linkage, bell-crank 40 4, pedal 6 etc., and the other the bolt, and that both work through the single throttle 2. This arrangement is preferred, though not indis- 45 pensable as will be evident.

In the particular embodiment illustrated in 50 55

Fig. 1, the cam bolt is operated in the direction to increase the fuel delivery, by a link 14 and bell crank 15 connected with a plunger or button mounted on the floor board of the vehicle, for example, and directly under, and in position to be engaged and operated by the pad of the normal clutch pedal 16, as indicated by the full and dotted lines. Opening the clutch as for making a gear change, thus advances the bolt and increases the engine speed, as above described, and the bolt continues in this position until the driver, having completed the gear shift and again closes the clutch, next uses the accelerator pedal, or otherwise further opens the throttle; thereafter, it will be understood, the engine comes to its normal idle whenever the driver ceases to control the engine as by removing his foot from the pedal. The period of increased engine speed thus covers the whole of the gear changing operation with its incident change of load and guards against engine stalling which is common on such occasions, especially with inexperienced drivers, and it relieves even the experienced driver of the need of attention to engine speed or of any haste in his foot movement. At the same time, it permits the normal idle to be set at a slower rate than might otherwise be practical and with corresponding fuel economy.

Figs. 4, 5 and 6 refer to the same type of throttle linkage, including the same normal engine-control element, or bell crank 4, which, as before, will be assumed merely to exemplify any member of the fuel supply system, and these figures also show the same type of cam or bolt 30 for increasing the speed above the idle, but in this case the increasing means or bolt has two stages of action. The first stage is represented by its bevelled end 10 and the second by its further bevel 11 separated from the first by the straight side or landing 11. When this bolt is advanced, it first depresses the hub 12, as before and as indicated in Fig. 5, and to the extent of the pitch of the bevel 10, thus slightly increasing the engine speed, and then depresses it further by contact with the second and higher bevel 11, still further increasing the speed. Removal of the actuating pressure on the bolt allows it to return at once to the position indicated in Fig. 5 wherein the hub 12 rests upon the landing 11 separating the two bevels and where the pressure of the hub holds the bolt against further retraction by the spring 13, as before, and until the throttle is again used by the driver. Thus the full movement of the speed increaser gives a considerable speed increase which is then automatically reduced to a less increase and held in that condition for the period during which an engine stall is likely.

This two stage speed increaser may be used 60 in place of the single stage bolt of Fig. 1 for momentarily accentuating the speed increase at the beginning of a gear shift period, if that should be desired, and either the single stage or the two stage may be connected for actuation by or as 65 the result of the use of a vehicle control element other than the clutch pedal, for instance by the element which is normally used by the driver for electrically starting the engine in rotation. In Fig. 1 the starter button 18 operates a plunger member 20 to close the switch of a starting motor 21 in the usual manner and, as shown enlarged in Fig. 4, the plunger member may also operate a bell crank 19, which in turn is connected to the cam bolt, the two stage bolt in this instance. 70 Full depression of the button, besides cranking

the engine, gives it an initial high speed action which is followed by a slower but brisk idle until it is put under load, after which the idle is normal.

It will be apparent, though not illustrated, that both of the two control elements referred to, that is to say, clutch and starter button, may be connected to operate the speed increaser; the invention comprehends the use of either or both or any of the normal control elements for this purpose and it contemplates also the use of the normal throttle control element as the means of terminating any condition or setting previously established by some other control element or fuel-increasing device as well as the speeded-up condition established by means such as described.
